UNITED STATES PATENT OFFICE.

GEORGE W. RICH, OF CAMDEN, NEW YORK, ASSIGNOR TO F. H. CONANT'S SONS, OF SAME PLACE.

DESIGN FOR A CHAIR-SEAT.

SPECIFICATION forming part of Design No. 23,452, dated July 10, 1894.

Application filed June 18, 1894. Serial No. 514,476. Term of patent 7 years.

To all whom it may concern:

Be it known that I, GEORGE W. RICH, a citizen of the United States, residing at Camden, in the county of Oneida and State of New York, have invented and produced a new and original Design for Chair-Seats, of which the following is a specification, reference being had therein to the accompanying drawings.

The leading feature of my design consists in the concave recess formed in the front of the seat and just rearward of which the seat is shaped to have an elevated part, from which the seat slopes downward rearwardly and laterally, the rear portion of the seat being most depressed.

In the accompanying drawings Figure 1 is a plan view of my newly designed seat and Figs. 2, 3 and 4 are sections on lines 2—2, 3—3, and 4—4, respectively, of Fig. 1.

A denotes the body of the seat having a curved or concave recess *a* in front, the seat being molded or shaped to have an elevated portion *b* just rearward of the recess *a*, from which elevated portion the seat slopes rearwardly and laterally, as shown by the sectional views Figs. 2, 3 and 4. Surrounding the depressed portion of the seat is an elevated rim portion *c*.

What I claim is—

The design for a chair seat, substantially as shown and described.

In testimony whereof I affix my signature in presence of two witnesses.

GEORGE W. RICH.
